Primary Examiner—Elizabeth A Albert(74) *Attorney, Agent, or Firm*—Calfee, Halter & Griswold LLP(57) **CLAIM**

I claim the ornamental design for a writing implement, as shown and described.

DESCRIPTION

FIG. 1 is a front/right/top view of the writing implement;

FIG. 2 is a front view thereof;

FIG. 3 is a rear view thereof;

FIG. 4 is a right side view thereof, wherein the left side view would be a mirror image thereof;

FIG. 5 is a top view thereof; and,

FIG. 6 is a bottom view thereof.

FIG. 7 is a front/right/top view of the writing implement with the cap removed and shown in the Figure;

FIG. 8 is a right side view thereof, wherein the left side view would be a mirror image thereof; and,

FIG. 9 is a front view thereof without the cap being shown in the Figure.

The broken lines immediately adjacent to the shaded areas represent the bounds of the claimed design, while all other broken lines are directed to environmental matter; the broken lines form no part of the claimed design.
